UNITED STATES PATENT OFFICE

HARRY E. UPHAM, OF WAKEFIELD, MASSACHUSETTS, ASSIGNOR TO UNITED SHOE MACHINERY CORPORATION, OF PATERSON, NEW JERSEY, A CORPORATION OF NEW JERSEY

ART OF MAKING SHOES

Application filed May 10, 1924. Serial No. 712,218.

This invention relates to improvements in the art of making shoes and is herein illustrated as concerned with a method of producing a so-called close shank effect in a shoe, 5 and as embodied in a shoe having what is known as a close fitting, or close edge shank.

In certain styles of shoes it is desirable to have the edges of the shank of the sole closely hug or engage the adjacent portion of the 10 upper so that the crease between the upper and the sole is substantially closed at the shank and a close shank effect is produced. It is often difficult, however, particularly in the manufacture of Goodyear welt shoes, to 15 produce and permanently retain this close shank effect. In the operation of attaching the outsole of a welt shoe the sewing instrumentalities enter the welt crease and force the welt, together with the sole margin, away 20 from the upper. Consequently, after the outsole stitching has been completed it has been necessary heretofore to pound or rub the soles with a great deal of force in order to 25 bend the edges of the shank toward the upper. Such heavy pounding frequently breaks the 30 outsole stitches or otherwise injures the shoe. Furthermore, in a welt shoe in which the outsole is pounded as above described, the bent portions at opposite sides of the shank are 35 not permanently set in the desired close relation to the upper and they are liable ultimately to pull away from the upper so that the 40 close shank effect is destroyed and the advantages incident thereto are lost.

In view of the foregoing, one object of the 45 present invention is to secure and permanently to retain a close shank or close edge effect such as above referred to, without subjecting the sole to heavy pounding or harsh treatment of any sort, or to any operations tending 50 to break the stitches or damage the sole.

With this object in view, the present invention provides an improved method which in one aspect consists in reducing the cohesion or resistance to stretching of the material at one side of a sole along a line extending lengthwise of the sole edge, and bending toward the opposite side of the sole the marginal portion adjacent to said line. 55 Preferably, and as illustrated, the reducing

operation will be accomplished by slitting the sole part way through upon the grain side at a blunt angle to the face of the sole and at a predetermined distance from its edge, the slit thus lying in a plane approximately parallel to the edge face of the sole. Preferably also the sole will be channeled before it is slit and the slit will be formed in the channel and adjacent to the base of the channel flap at each side of the shank portion of the sole. The channeling and slitting operations may occur simultaneously and they may be effected by the operation of a single cutting tool upon an unattached sole, or the slitting may take place either in conjunction with the rough-rounding and channeling operation upon an attached sole, or after the rough-rounding and channeling operation has been completed. In the latter cases, the channel flap will be turned back to open the channel before the slitting takes place and the turned channel flap may advantageously be utilized to guide the slitting knife so as to locate the slit at or near the inner edge of the channel. After a sole has been slit as above described, 70 its margin, because tensional strains are avoided in the outer portion of its thickness, is rendered capable of being bent to produce a close shank effect by means of a comparatively light pressure which has no tendency to break the stitches attaching the sole to the shoe or otherwise to damage the sole.

In soles made of leather, the stock adjacent to the grain side or tread face of the sole, is tougher and denser than the stock at the flesh or inner side of the sole and the difficulty experienced in bending the sole margin toward the upper is largely due to the toughness and resistance to stretching of the stock at the grain side of the sole. The outer portion of the stock at this side of the sole not only resists strongly the bending of the sole margin because of tensional strain set up in said portion, but tends, because of such strains, to return the margin to its original flat condition after it has been bent out of the plane of the body of the sole. In operating upon leather soles the slit, which is made in accordance with the present inven- 100

tion for the purpose of facilitating the bending of the sole margin, is located in the tough and dense material at or adjacent to the grain side of the sole and effectively relieves the resistance to stretching and bending which is offered by this portion of the sole. Further to facilitate the bending of a leather sole, and in accordance with another characteristic of the present invention, the sole is advantageously moistened or tempered before it is subjected to the channeling or slitting operations and while still in temper the sole may be operated upon by light pounding devices or other means for the purpose of pressing the sole margin into the desired relation to the upper. The resistance offered by the grain side of the leather to the bending of the sole margin having been removed by the slitting above described, it is comparatively easy to bend or offset the sole margin to any extent desired, the slit opening up to permit the bending to take place without stretching, or setting up tensional strains in, the material at the grain side of the sole, that is, in the outer portion of its thickness. After the sole margin has been bent the sole is allowed to dry and as it dries the sole material shrinks in such a way that the sole tends to bend or curl transversely toward the flesh side thereof. This is chiefly on account of the fact that the surface at the flesh side of the sole is continuous throughout its entire length, whereas the continuity of the surface at the grain side of the sole is interrupted widthwise of the sole by the slits made therein. After the margin of a tempered sole has been bent toward the upper and thereafter allowed to dry, it will be permanently set in its bent condition as a result of the shrinkage of the leather, the shrinkage being more effective at the flesh side than at the grain side of the sole, as above explained. Moreover, after the sole margin has been bent to the desired extent, if the sole has been channeled, the laying of the channel flap to close the channel and the cementing of the channel flap in place upon the bent margin of the sole, tends effectively to prevent reverse bending of the sole margin and thus insures that the close shank effect will be permanently retained.

A further feature of the present invention is to be recognized in the provision of a new article of manufacture comprising a sole having a slit or depression at one side thereof extending lengthwise of and located adjacent to the sole edge, the slit lying in a plane approximately parallel to the edge face of the sole, the purpose of the slit being to reduce the cohesion of the material at the slit side of the sole so as to facilitate the bending of the sole margin toward the opposite side of the sole. Preferably the slit is cut within a stitch-receiving channel formed in the grain side of a leather sole and is directed down-

wardly into the sole material at or near the base of the channel flap.

In the accompanying drawings,

Fig. 1 is a plan view of the outer or bottom face of an outsole showing the location there-
in of slits made in accordance with the method of the present invention for the purpose of adapting the edges of the sole for snug engagement with the upper at the shank of the shoe;

Fig. 2 is a cross-sectional view through the shank portion of a Goodyear welt shoe in process of manufacture, showing particularly the outsole after it has been channeled and slit in accordance with the present invention, but before it has been attached to the welt and bent toward the upper;

Fig. 3 is a sectional view, similar to Fig. 2, but showing the outsole as it appears after it has been attached to the welt and after the opposite edge portions of the shank have been bent against the upper;

Figs. 4 and 5 are cross-sectional views through the shank of an outsole for a McKay sewed shoe showing the location of slits for facilitating the bending of the sole to produce a close shank effect; and

Fig. 6 is a bottom plan view of a welt shoe the outsole of which has been channeled to receive stitches along the inner edge only of the shank, the sole having been stitched "aloft" along the other portions of its margin.

Referring first to Fig. 2, the outsole of a Goodyear welt shoe is indicated at 6, the insole at 8, the upper at 10, the welt at 12, and the last at 14. The welt, the upper and the insole are secured together in the usual manner by means of inseam stitches 16 and a suitable filler 18 is applied to the insole.

In accordance with one manner in which the method of the present invention may be practised the outsole 6, having first been tempered, is coated with cement and laid upon the lasted shoe. The sole is then rough- rounded and channeled in the usual manner, the channel being indicated at 20. After the channeling operation has been completed, the channel flap 22 is raised and a slitting knife is drawn along the base of the channel flap at each side of the shank, the knife cutting downwardly into the material of the sole to make the slits 24 at a blunt angle to the face of the sole, said slit preferably lying in a plane approximately parallel to the edge face of the sole.

By drawing the slitting knife 120 along the inner extremity of the channel, the knife may be guided so that each slit will be located at the base of the corresponding channel flap. It may be convenient to incline the slitting knife somewhat to the perpendicular 125 so that the slit will be inclined downwardly and inwardly with respect to the plane of the channel as herein illustrated. If desired the slit may be spaced outwardly more or less from the inner edge of the channel. Suita- 130

ble provision should be made for limiting the distance to which the slitting knife is permitted to penetrate into the material of the sole. In practice, the extent of the amount of penetration of the slitting knife will vary in accordance with the thickness of the sole being operated upon.

While the channel flap remains in raised position, the welt and the outsole are secured together by means of stitches, such as indicated at 26 in Fig. 3, the stitches being received in the channel 20. The opposite margins of the sole at the shank may then be pressed or bent toward the upper by light pressure exerted by any suitable means such as the tool of a rotary pounding machine. Before the channel flaps are laid, the sole is permitted to dry. As the sole dries, the shrinkage of the material at the inner or flesh side thereof exerts tension on the marginal portions of the sole which tends to hold the latter in their bent positions in close engagement with the upper. It will be noticed that the sides of the slits separate somewhat as shown in Fig. 3 to enable the sole margins to be bent backwardly without stretching or tensioning the material at the grain side of the outsole. The tension or transverse pull resulting from the shrinkage of the material at the outer or grain side of the sole is rendered ineffective to offset the tension at the inner face of the sole by the opening of the slits 24. As a result, the bent margins of the sole are permanently set in engagement with the upper and there is practically no influence tending to restore them to the plane of the body of the sole. Even if the sole margins are not pressed back into close engagement with the shoe upper, the herein-described slitting of the sole margin serves materially to relieve the strain upon both the inseam and outsole stitches and as a result the stitches are rendered less liable to give way along the slit portions of the sole. After the sole has become thoroughly dry, the channel flaps are laid to close the channel and cover the stitches and the flaps are firmly cemented in place, as shown in Fig. 3. The cemented channel flaps serve as additional means for insuring that the sole margin will be permanently retained in its bent condition.

In case it may be desired to manufacture shoes with a close inside shank and a straight outside shank, or vice versa, it is to be understood that the slits may be made at either the inside or outside marginal portions of the shank of the sole instead of at both marginal portions as above described.

In making welt shoes a close shank effect along the inside margin of the shank may be produced by channeling the inside margin of the shank, slitting the material beneath the channel flap as shown at 40 in Fig. 6, attaching the outsole to the welt and upper

by stitching "aloft," i. e., causing the stitches to lie substantially flush with the tread face of the sole, along the outer margin of the shank and at both sides of the forepart as indicated in full lines at 42 in Fig. 6, and by stitching within the channel along the inner margin of the shank, as indicated by dotted lines at 44 in said figure, and thereafter pressing backward toward the upper the channeled inside shank portion of the sole.

The invention is not necessarily limited to the cutting of the slit in the channel of a sole since it may be found desirable in some cases to cut the slit directly in the grain or tread face of the sole, either before or after the sole is attached to the shoe. If cut directly in the tread face of the sole the slit, which is opened more or less by the subsequent bending of the sole margin, may be filled with suitable filler material in order that the continuity of the tread face of the sole shall not be interrupted by the slit.

The method of the present invention is not limited in its application to the construction of shoes in which the margin of the outsole lies close to the upper only at the shank of the shoe, but may apply also to shoes in which other portions of the sole margin are bent toward the upper. For example, an outsole for a welt shoe may be channeled and slit around the toe and along both edges of the forepart, as well as along both edges of the shank to facilitate the flexing or bending of the sole to produce the so-called "ball-bottom" effect in imitation of a turn shoe. The various steps of the herein described method may be performed upon outsoles for McKay sewed shoes, as well as upon outsoles for welt shoes. When outsoles for McKay shoes are slit in accordance with the method of this invention, the sole margins will hug the upper more closely at the portions of the sole which are slit than would be the case if the slitting operation were not performed.

In McKay work, the outsole is commonly channeled before the sole is located upon the shoe. A McKay outsole is shown at 28 in Fig. 4 and the usual channel is indicated at 30, the channel having a groove 32 formed therein for receiving the outsole stitches. The slit for facilitating the bending of the sole margin may be made along a line located at the inner side of the groove 32 at either or both sides of the shank, as shown at 34. When a sole slit in this manner is secured to the upper and insole of a shoe by the operation of the McKay sewing machine the stitches serve to pull the sole margin close to the upper so that the close shank effect may be produced and retained without requiring the application of pressure to the sole margin by pounding or otherwise. If desirable, the slit may be made at the outer

side of the groove 32, or at both sides of the groove 32 as shown at 36 and 38 in Fig. 5.

Having described the invention and the preferred method of practicing it, what is claimed as new is:

5 1. That method of fitting outsoles which consists in reducing the cohesion of a portion of the thickness of the material at one side of the outsole along a line extending 10 lengthwise of the sole edge without affecting the edge thickness of the sole, bending toward the opposite side of the sole the marginal portion adjacent to said line, and permanently setting said marginal portion in its bent condition.

15 2. That improvement in methods of making shoes which consists in slitting the sole part way through at one side at a predetermined distance from its edge and approximately parallel to its edge face, and bending the margin of the sole after its attachment to a shoe into close relation to the upper.

20 3. That improvement in methods of making shoes which consists in maintaining the edge thickness of the margin of an attached outsole unaltered, reducing the cohesion of a portion of the thickness of the sole along a line inwardly of its margin in which portion strains are produced in forcing said margin 25 toward the upper, and closing the crease between the sole margin and the upper by bending said margin toward the upper.

25 4. That improvement in methods of making shoes having close shanks which consists in maintaining the edge thickness of the margin of an attached outsole unaltered, reducing the cohesion of a portion of the thickness of the shank of the sole along a line inwardly of its margin in which portion tensional 30 strains are produced in bending the margin toward the upper, and closing the crease between the sole margin and the upper along the shank of the shoe by bending said margin toward the upper.

40 5. That improvement in methods of making close shanks in welt shoes which consists in rough-rounding and channeling an attached outsole, lessening the resistance to bending of the outer portion of the thickness 45 of the sole by a cut made at a blunt angle to the inner face of the sole and extending along the base of the channel flap from ball line to breast line, bending the sole margin to close the welt crease at the shank portion of the shoe, and cementing and laying the channel flap to maintain the welt crease closed.

55 6. The method of fitting soles which consists in cutting into the material at one side of a sole to form a stitch-receiving channel 60 and a channel flap, and slitting the material at the side of the channel opposite the channel flap lengthwise of the channel in a plane substantially parallel to the edge face of the sole to facilitate the bending of the portion of the sole at the outer side of the slit into snug

engagement with the adjacent portion of a shoe upper attached to the sole.

7. The method of preparing leather outsoles to adapt the edge of a sole to lie close to the upper of a shoe to which the sole is to be attached which comprises tempering the sole, and cutting into an outer portion of the thickness of the sole while the sole is in temper to form a slit extending lengthwise of the sole edge and directed downwardly and inwardly with respect to the shoe at an obtuse angle to the inner face of the central portion of the sole so as materially to lessen the resistance of the sole to bending along the line of the slit.

80 8. That improvement in the art of making shoes which consists in forming in a sole a stitch-receiving channel and a slit extending lengthwise of the sole edge and downwardly from the channel toward the unchanneled face of the sole, and bending the marginal portion of the sole along the line weakened by the slit.

85 9. That improvement in the art of making shoes which consists in forming a channel and a channel flap in the grain side of a sole, cutting a slit within the channel and adjacent to the base of the channel flap, bending the sole margin toward the flesh side of the sole, and cementing the channel flap to the sole margin to prevent reverse bending of the sole margin.

90 10. That improvement in the manufacture of shoes which consists in forming a marginal channel at the grain side of an outsole, slitting from within the channel toward the unchanneled face of the sole, and attaching the sole to the shoe by stitches received in said channel, and extending through the portion of the sole outside of said slit.

100 11. That improvement in the manufacture of welt shoes which consists in laying the outsole upon a lasted upper to which the welt has been attached, rough-rounding and channeling the outsole, slitting the material at the base of the channel flap downwardly toward the inner side of the outside along the shank thereof, stitching the outsole and welt together, and applying pressure to the portion of the outsole outside of the slit to bend it 115 snugly against the upper.

120 12. A new article of manufacture comprising an outsole having, through an outer portion of its thickness, a slit lying approximately parallel to the edge face of the sole to reduce the cohesion of said margin and facilitate bending of the margin of the sole toward the unslit side.

125 13. A new article of manufacture comprising an outsole having a slit in the margin thereof and extending part way only through the thickness of said margin, said slit lying in a plane approximately parallel to the edge face of the sole to facilitate bending of said

margin out of the plane of the body of the sole.

14. A new article of manufacture comprising a sole having a stitch-receiving channel and a channel flat at one side thereof, and a slit positioned in the channel and extending lengthwise thereof in the material at the side of the channel opposite the channel flap.

15. A new article of manufacture comprising a sole having a stitch-receiving channel and a channel flap at one side thereof, and a slit positioned in the channel and extending lengthwise thereof adjacent to the base of the channel flap, at the shank portion of the sole.

16. A welt shoe having an outsole provided with a stitch-receiving channel and a channel flap extending along the inner margin of its shank, and a slit extending lengthwise of said channel in the material covered by the channel flap, the outsole being attached to the welt and upper by means of stitches which lie within said channel along said inner margin of the shank but which are exposed at the thread face of the sole at other portions of the sole margin and the margin of the sole adjacent to said slit being bent toward the upper to produce a close shank effect.

In testimony whereof I have signed my name to this specification.

HARRY E. UPHAM.
